NIPPLE FOR VALVE DRINKING DEVICES FOR ANIMALS

Helmut Rader, 16 Bahnhofstrasse,
6079 Buchschlag, Germany
Filed Jan. 12, 1970, Ser. No. 20,869

Claims priority, application Germany Aug. 22, 1969

Term of patent 14 years

Int. Cl. D30—03

U.S. Cl. D30—13

FIG. 1.

FIG. 1 is a perspective view of a nipple for valve drinking devices for animals showing my new design;

FIG. 2 is a top plan view of said nipple; and
FIG. 3 is a bottom plan view of said nipple.

I claim:

The ornamental design for a nipple for valve drinking devices for animals, as shown and described.
